UNITED STATES PATENT OFFICE.

LEONARD L. LESOINE, OF EAST STROUDSBURG, PENNSYLVANIA, AND FREDERICK C. EMMEL, OF NEW YORK, N. Y.

BUILDING CONSTRUCTION.

Application filed June 19, 1925. Serial No. 38,366.

Our invention relates to a construction for walls and ceilings, hereinafter referred to as a wall construction and particularly relates to a structure adapted to be embodied 5 in the form of a unit to be incorporated in a wall or a ceiling as a unit.

The general object of our invention is to provide a building construction unit that may be made of any desired height or width 10 to suit a particular room or location and in which sheet metal elements are given a form to function as studdings in association with members constituting braces for the studding members.

15 The nature of the invention and its distinguishing features and advantages will clearly appear as the description proceeds.

Reference is to be had to the accompanying drawings forming a part of this specification, it being understood that the drawings are merely illustrative of practical examples of the invention.

Figure 1 is an elevation of a building construction unit embodying our invention, 25 showing the same in association with parts employed in connection with a plurality of units as hereinafter explained;

Figure 2 is a vertical section on the line 2—2, Figure 1, a portion of the wire lathing, which in practice is applied to a plurality of units, being omitted;

Figure 3 is a fragmentary horizontal section in a plane corresponding with the line 3—3, Figure 1 and showing lathing and surface material;

Figure 4 is a fragmentary view in vertical section illustrating a slight modification;

Figure 5 is a horizontal section through 40 a unit embodying my invention in modified form, the view including lathing which in practice is applied to a plurality of units;

Figure 6 is a view similar to Figure 5 but illustrating a further modification.

45 In producing a building unit in accordance with our invention, a frame is provided, comprising side uprights 10 usually of wood elements of substantially the character of studdings. In addition in practice, 50 a top cross bar 11 and a bottom cross bar 12 are provided also of wood and arranged to connect up a plurality of the units to form the wall or ceiling. To the side uprights 10, we apply a sheet metal covering, 55 designated generally by the numeral 13

which is bent to form members 14 disposed in planes perpendicular to the general plane of the unit, that is to say, at substantially right angles to the front and rear faces of the unit. The material of the metal sheet 60 13 between adjacent members 14 is given an oblique direction to form members 15 extending from the front edge of one member 14 to the rear edge of the adjacent member 14. The members 14 serve as studdings 65 and resist strains or stresses at right angles to the faces of the units, while the members 15 constitute inclined braces integral with the studding members 14. The upper and lower edges of the sheet 13 are bent at right 70 angles to produce flanges 16 to be applied to the upper and lower cross bars 11, 12. Suitable lathing is applied to the faces of the inner and outer sides of a plurality of units for joining the same edge to edge, 75 there being shown metal lathing 17 in Figure 2, the metal lathing being secured by integral members 18, struck up from the material of sheet 13, whereas, in Figure 4, 80 separate clips 118 are employed to fasten the lathing 17 in place.

A suitable wall covering material is applied to the inner and outer faces of the units forming a wall or ceiling, as for example, the one covering 19 may be concrete 85 or equivalent material suitable for the outside of a wall, and the surface 20 may consist of plaster at the inside of the wall, see Figure 3.

In Figure 5 instead of the form shown in 90 Figures 1 to 4, the framework is provided with wooden studding members 21 adjacent to the respective faces of the unit and in staggered relation. The vertical wood studding members 21 complete studding elements 95 in association with the members 114 of the metal sheet 113, said members 114 being disposed between the stud members 21 and, like the members 14, said members 114 are perpendicular to the planes of the faces of the unit. The metal sheet 113 includes in addition to members 114 members 115 extending from the front edge of one member 114 to the rear edge of the adjacent member 114.

100 In the form shown in Figure 6 wood studding members 121 are employed and are disposed adjacent to the planes of the front and back surfaces of the unit. In comparing the 105 constructions in Figures 5 and 6, it will be 110

23
noted that in Figure 5 the wood studding members 21 are adjacent to a common transverse plane whereas in Figure 6, studding members 121 at the back and front are disposed equal distances apart and separated one from the other. The metal sheet 213 in Figure 6 is bent into zig-zag form so that oblique members 215 constitute both studding members and brace members.

10 The described constructions serve to effectively resist stresses produced by pressure against the faces of the unit and at the same time resist crushing strain vertically.

15 To each of the faces of a plurality of units such as shown in Figures 5 and 6, the wire lathings 17 referred to above are applied the same as in the first described construction.

20 The numeral 22 indicates terminal side edge flanges on the sheet material 13 for nailing said material to the upright side frame members 10. The numeral 23 indicates tongues integral with the material of the sheet 13 at the top edge thereof and disposed at the back and front of the top member 11. Similarly, integral tongues 24 are provided on the sheet material 13 at the bottom edge to receive fastening nails for securing said material to the bottom rail or bar 12.

25 30 We would state furthermore, that while the illustrated examples constitute practical embodiments of our invention, we do not limit ourselves strictly to the exact details herein illustrated, since, manifestly, the same

can be considerably varied without departure from the spirit of the invention as defined in the appended claims. 35

Having thus described our invention, we claim:

1. A building construction unit adapted 40 to be emplaced in a wall or a ceiling and having a metal sheet, said sheet presenting studding members disposed in transverse planes and presenting oblique members between the studding members and extending 45 from the front edge of one studding member to the rear edge of an adjacent studding member.

2. A unit for building construction including a frame having upright studding members, and a metal sheet extending over said frame and coacting with said members to constitute studding, said members being disposed adjacent the inner and outer sides of the unit and said sheet metal being disposed between said members and secured to the inner sides thereof. 50

3. A unit for building construction including a metal sheet having transverse studding members terminating in planes at the front and back of the sheet, and oblique members integral with said studding members and extending from that edge of one studding member lying in one of said planes to the opposite edge of the next studding member 60 lying in the other of said planes. 65
